UNITED STATES PATENT OFFICE.

JOHN H. THAISON, OF CHICAGO, ILLINOIS.

ROLLER FOR PRODUCING ALTO-RILIEVO ORNAMENTATION.

SPECIFICATION forming part of Letters Patent No. 380,833, dated April 10, 1888.

Application filed July 5, 1887. Serial No. 243,472. (No model.)

To all whom it may concern:

Be it known that I, JOHN H. THAISON, of Chicago, in the county of Cook and State of Illinois, have invented a new and Improved 5 Roller for Producing Alto-Rilievo Ornamentation, of which the following is a full, clear, and exact description.

My invention has for its object to provide a roller to be used for producing ornamentation in alto-rilievo in plastic composition applied to picture-frame moldings, house-trimmings, or any other foundation material, and by the aid of an embossing-press in which the roller will be journaled opposite a bed holding 15 the work.

The invention consists in certain novel features of construction of the roller, as herein-after described and claimed.

Reference is to be had to the accompanying 20 drawings, forming a part of this specification, and in which—

Figure 1 is a perspective view of my improved roller, and Fig. 2 is a face view of a piece of molding, having alto-rilievo ornamentation produced by the roller.

The roller is made with a rim or periphery, A, which is supported at its central part from the hub B by a flange, C, and where the rim of the roller is broadened considerably, to 30 accommodate designs of considerable width, such, for instance, as the laterally-projecting parts of leaves, flowers, or the like, radial ribs or fins D will be cast or fixed between the rim A and hub B, at one or both sides of the 35 flange C, as will be understood from Fig. 1 of the drawings. A key-seat, a, in the roller-hub provides for fixing the roller to a shaft of any suitable embossing-press.

In finishing the roller, its rim A will first 40 be turned true, and then the particular design E, to be produced in alto-rilievo in a plastic composition applied to a molding, F, or other plate, strip, or structure to be ornamented, will be cut into the peripheral face of the roller, 45 or be produced *in intaglio* thereon, and the margins of the rim A at each side will then be cut away to correspond with the marginal outlines of the design, and produce thereat suitable cutting-edges which will trim the plastic composition from the outer margins of the design, 50 and where there are inside openings, g, in the design the rim of the roller will be formed with

correspondingly-shaped slots or openings, G, which will flare from the outer face of the rim A to its inner face, to give ample clearance to 55 those portions of the composition which are cut away by the margins of the openings G to pass through these openings and be discharged at the inside of the rim of the roller.

In producing the ornaments on the molding F, or other work, a strip of any suitable plastic composition backed with glue or other adhesive substance will be laid upon the molding, which will then be passed over the bed of any suitable press, in which the roller 65 will be journaled in position to operate on the composition and cut away the composition at the outer margins of the various parts of the pattern of the ornament, and also at the interior openings, g, of the ornament, as will readily 70 be understood.

The ornamentation E shown consists of stems, leaves, and acorns suitably arranged to give a pleasing finish to moldings intended for use in making picture-frames; but the ornament may have any desired design in high or low relief, and may be applied to door-casings or other house-trimmings, or any other base or foundation, in making a variety of ornamented useful products.

Having thus described my invention, what I claim as new, and desire to secure by Letters Patent, is—

1. A roller for producing alto-rilievo ornamentation, made with a rim on the face of 85 which are produced sunken or intaglio patterns, and said rim being cut away to conform to the outer margins of the patterns, and also cut through to conform to inside openings of the patterns, substantially as described, for 90 the purposes set forth.

2. A roller for producing alto-rilievo ornamentation, comprising a rim, A, held to a suitable hub adapted for connection to a driving-shaft, and said rim cut away at both side 95 edges, to conform to the outer margins of patterns produced *in intaglio* on its face, and also cut through at G to conform to the margins of inside openings of the patterns, substantially as herein shown and described.

JOHN H. THAISON.
